UNITED STATES PATENT OFFICE

2,479,597

DOORSTOP

Nickolas T. Anton, Park Ridge, Ill., assignor to
Wesco Electric Company, Inc., Chicago, Ill., a
corporation of Illinois

Application July 23, 1948, Serial No. 40,398

1 Claim. (Cl. 16—86)

1

This invention relates to certain new and useful improvements in a door stop device and more specifically to a spring cushioned door stop device which is simple and inexpensive in construction and adapted to the purpose of cushioning the impact or shock of a door when opened.

Heretofore door stop devices have been used which incorporated a spring for cushioning or receiving the impact of the force exerted by a door, but such prior door stop devices have been subject to a number of shortcomings and objectionable characteristics. In general such prior door stop devices have been of complex and cumbersome construction and have required means arranged externally of the body of the door stop device itself for installing the same, thus producing an unornamental and inartistic appearance.

Accordingly an object of the present invention is to provide a new and improved inexpensive door stop device embodying a simple, sturdy, and durable construction which may be easily installed.

Another object of the invention is to provide a suitable door stop which will provide means for cushioning the opening movement of a door so as to prevent undesirable noise, as well as limit the opening movement of the door without marring the baseboard or wall surface adjacent thereto.

A further object of the invention is to provide in the new door stop novel means for installing the same whereby the new door stop may be easily and quickly applied to the baseboard of the wall structure adjacent to the door, and when so installed, presents an ornamental compact appearance which is due, in a large measure, to the fact that the means for installing the device are arranged within the body of the device itself.

Other and further objects of the present invention will be apparent from the following description and claim and are illustrated in the accompanying drawings, in which:

Fig. 1 is a perspective view showing the new door stop device secured to the baseboard of a wall structure;

Fig. 2 is an enlarged longitudinal sectional view, showing the new door stop device mounted upon the baseboard;

Fig. 3 is a transverse sectional view on line 3—3 in Fig. 2; and

Fig. 4 is a transverse sectional view on the line 4—4 in Fig. 2.

A preferred embodiment of the new door stop device is generally indicated at 10 in the drawing and is shown as being mounted in position upon the baseboard 11 of the vertical wall structure

2

12 which defines one side of a room to which access may be had through a door opening 13, adapted to be closed by a hinged door 14, which is arranged above and perpendicular to the floor 15 of the room.

The new door stop device comprises a cylinder 16 having a base portion 17 which is provided with a central aperture 18 and concave or countersunk recess 19 adjacent to the central aperture 18, so as to accommodate a flat headed anchoring screw 20. The anchoring screw 20 is passed through the central aperture 18 in order to mount the cylinder 16 horizontally upon the baseboard 11 adjacent to the door 14.

15 A collar bearing 21 is removably mounted within the other end portion 21 of the cylinder 16 and is firmly secured to the wall of the cylinder by means of a set screw 22 which projects through an aperture 23 which is formed in the wall of the cylinder 23 and into a threaded opening 24 which is formed in the collar bearing 21.

20 The collar bearing 21 is held in a fixed position when the set screw 22 is threaded into the threaded opening 24 which is formed in the collar bearing 21.

25 A plunger 25 is slidably mounted within the collar bearing 21 and a rubber or like resilient bumper 27 is removably mounted upon the outer end portion of the plunger 25. To this end the rubber or like resilient bumper 27 has a recess 26 formed therein for the reception of the outer end portion of the plunger 25. The opposite and internal end portion of the plunger 25 is provided with an enlarged flange portion 28 which acts as a stop when it comes into contact with the annular collar bearing 20, thus restricting the extent of the horizontal movement of the plunger 25 and thereby preventing the plunger 25 from escaping from the cylinder member 16.

30 Disposed within the cylinder member 16 is a substantially cylindrical helical spring 29 one end portion of which bears against the enlarged abutment portion 28 of the plunger 25 while its opposing end portion abuts the bearing surface provided by the base portion 17 and the head of the anchoring screw 20.

35 The use and operation of the new door stop device shown in Figs. 1 to 3, are as follows:

40 The new door stop device 10 is shown in Fig. 1 of the drawing in the position in which it may be disposed upon the baseboard 11 of a vertical wall structure 12 which defines one side of a room. By reference to Fig. 2 it will be noted that the new door stop device 10 is retained in operating posi-

tion upon the baseboard 11 by the engagement of the anchoring screw 20 with the baseboard 11.

When the substantially cylindrical helical spring 29 is distended to its full extent the plunger 25 is disposed as in Fig. 2 and projects partially from the cylinder 16. However, when the flange 28 comes into contact with the annular collar bearing 21 which is securely held in place by the set screw 22, the horizontal movement of the plunger 25 is terminated and the flange 28 of the plunger 25 rests adjacent to the collar bearing 21.

When the new door stop device is secured to the baseboard 11 adjacent to the door 14, and the door is opened with considerable force so as to violently contact the rubber or like resilient bumper 27 mounted on the end portion of the plunger 25, the plunger member 25 will be forced inwardly, thereby compressing the substantially cylindrical helical spring 29. After the spring 29 has received the impact from the door 14, it will return the plunger 25 to its original position as shown. The strength of the spring 29 may be made commensurate to the force exerted by the door 14 on the plunger 25, and therefore will absorb all of the shock which would tend to vibrate the door 14 or cause damage to the vertical wall structure 12.

While I have shown the new door stop device as applied to the baseboard of the vertical wall structure, it will be understood that the new door stop device may, if desired, be secured to the door rather than to the wall structure, and is equally effective in either of said positions.

It will be seen from the foregoing description, considered in conjunction with the accompanying drawing, that the new door stop device accomplishes its intended objects, and has the desirable advantages and characteristics, including those hereinbefore pointed out and others which are inherent in the invention.

While I have illustrated and described the preferred embodiment of my invention, it is to be understood that this is capable of variation and modification and I therefore do not wish to be limited to the precise details set forth, but desire to avail myself of such changes and alterations as fall within the purview of the following claim:

I claim:

A door stop device comprising a substantially cylindrical member having an open end portion and including a base portion at its opposite end which is adapted to be mounted upon a vertical supporting surface, said base portion having a centrally arranged opening formed therein for the reception of a fastening element adapted to be passed through the said centrally arranged opening in the said base portion of the substantially cylindrical member and into the said vertical wall supporting surface, a collar guide member removably mounted in the said open end portion of said substantially cylindrical member, means for securing said collar guide member within the said open end portion of the said substantially cylindrical member including a threaded opening formed in the said collar guide member, and a manually operable set screw mounted in a wall of the said substantially cylindrical member and having an inner end portion adjustably mounted in the said threaded opening in the said collar guide member, a plunger slidably mounted in the said collar guide member and having a resilient bumper removably mounted thereon exteriorly of the said substantially cylindrical member, and a substantially cylindrical helical spring disposed within the substantially cylindrical member and including an end portion bearing against the base portion of the said substantially cylindrical member and having its other end portion bearing against the inner end portion of the said plunger member.
